CLAIM

The ornamental design for a flush valve as shown and described.

DESCRIPTION

FIG. 1 is a perspective view of a flush valve showing our new design.

FIG. 2 is a front view of the flush valve of FIG. 1.

FIG. 3 is a rear view of the flush valve of FIG. 1.

FIG. 4 is a left side view of the flush valve of FIG. 1.

FIG. 5 is a right side view of the flush valve of FIG. 1.

FIG. 6 is a top view of the flush valve of FIG. 1; and,

FIG. 7 is a bottom view of the flush valve of FIG. 1.

The evenly spaced broken lines in the drawings show portions of the flush valve, which form no part of the claimed design.

1 Claim, 7 Drawing Sheets
